UNITED STATES PATENT OFFICE.

CALVIN J. WHITE, OF MARSHALLTOWN, IOWA.

FASTENING DEVICE FOR DEMOUNTABLE RIMS.

Application filed March 9, 1923. Serial No. 623,851.

Heretofore with the fastening devices now employed for securing demountable rims to wheels, considerable difficulty and inconvenience has been experienced in that 5 considerable time and labor are necessary to perform the operations, in addition to which special tools are required.

It is one of the objects of the present invention to provide an improved simple, durable, and compact fastening device by means 10 of the use of which the rim may be readily and quickly attached to and secured upon the wheel and as readily removed therefrom without necessitating the use of any special 15 tools, and at the same time insuring that the rim will be properly positioned upon the wheel, which latter is not always the case with the fastening devices employing the wedge shaped elements which are usually 20 forced between the wheel felly and the rim.

To the attainment of these ends and the accomplishment of other new and useful objects as will appear, the invention consists in the features of novelty in substantially the 25 construction, combination, and arrangement of the several parts hereinafter more fully described and claimed and shown in the accompanying drawing illustrating this invention and in which

30 Figure 1 is a side elevation partially broken away of a portion of a wheel having a rim secured thereto, constructed in accordance with the principles of this invention.

Figure 2 is a view partly in elevation and 35 partly in vertical section of one form of fastening device.

Figure 3 is a view similar to Figure 2 of a modified form of the invention.

Figure 4 is a detail perspective view of a 40 portion of a wheel rim.

Figures 5, 6, and 7 are views of details.

Figure 8 is a view partly in side elevation and partly broken away of a wheel having the fastening devices applied thereto.

45 Referring more particularly to the drawing the numeral 10 designates generally a wheel of any desired construction but in the present invention the wheel is shown provided with spokes, 11.

50 The rim of the wheel is provided with any number of casings 12 according to the number of fastening devices it is desired to use and these casings are formed in any desired or suitable manner preferably by being formed integral therewith. As the construction of each fastening device is the same

the description of one will apply to them all. The casing is provided with a recess 13 therein opening through the top thereof as at 14 and the portion of the rim of the wheel 60 adjacent said casing is preferably recessed as at 15 for a purpose to be hereinafter set forth. The recess 13 in the casing 12 opens through the bottom of the casing and is preferably reduced adjacent its bottom to 65 form a shoulder 16.

Arranged within the casing is a bolt 17, the end 18 of which projects through the bottom of the casing and the end 19 projects through the top of the casing and is adapted 70 to be extended beyond the periphery of the felly of the wheel.

A coil spring 20 is arranged within the recess 13 and encompasses the bolt 17. One end of the spring is secured as at 21 to the 75 bolt 17 and the other end 22 of the spring is anchored in any suitable manner to the casing, preferably by inserting the end of the spring in a recess 23 in the bottom of the recess 15.

80 The spring 20 is of such a length that the bolt 17 may be shifted longitudinally with respect to the casing to expand the spring 20 and to permit the spring to contract in a manner to be set forth. A suitable plate 24 85 of a size and configuration to fit within the recess 15 is provided and is secured in position in any suitable manner such as by means of fastening screws 25 passing through suitable openings 26 in the plate. 90 The plate is provided with an opening 27 therethrough adapted to register with the opening 14 in the top of the recess 13 and the diameter of the opening 27 of the plate 24 is preferably considerable less than the 95 diameter of the opening 14 and is only slightly greater than the external diameter of the end 19 of the bolt 17, which is adapted to pass through the opening 27. The plate 24 is of a thickness that when inserted in the 100 recess 15 the upper face thereof will be flush with the periphery of the felly.

An operating lever 28, preferably provided with a laterally deflected bifurcated extremity 29 is provided for shifting the bolt 19 in one direction. This extremity 29 of the lever is provided with cam shaped portions 30 and the lever is connected with the extremity of the bolt 17 preferably by means of a pin 31, and which pin may be 110 held in position by means of suitable cotter pins 32, or other suitable devices which will

permit the pin 31 to be removed when desired so as to detach or attach the lever 28 with the end of the bolt 17.

When the lever 28 is connected with the bolt 17 it is adapted to be moved about the pivot pin 31 so that the surfaces of the cams 30 will engage the lower extremity 33 of the casing 12 to move the bolt 17 downwardly from the position shown in full lines in Figures 1 and 2 to the position shown in dotted lines in Figure 2. Inasmuch as the end 22 of the spring 20 in Figure 2 is anchored and the end 21 is connected with the bolt 17, the spring 20 will be placed under tension by this movement of the bolt so that when the lever 28 is moved from the dotted line position into the full line position in Figure 2, the contraction of the spring 20 will cause the end 21 of the bolt 17 to be projected from the casing. The deflected portion 29 of the lever 28 is adapted to stand beneath the lower face 33 of the casing 12 while the body portion of the lever 28 rests against the lateral face of the casing 12 and the extremity 34 of the lever is preferably deflected or shaped as shown, so as to permit the insertion of an instrument between the lever and casing to initially move the lever 28 so as to permit the same to be grasped by the hand of the operator, when it is desired to retract the bolt 17.

Suitable projections or ribs 35 may be provided on the side of the casing and between which ribs or projections the lever 28 is adapted to stand for the purpose of protecting the lever.

The rim 36 is preferably provided with a slightly depressed portion 37 adapted to be positioned so as to receive the extremity of the bolt 17 and a filler plate 38 is preferably arranged between the periphery of the felly of the wheel and the rim 36 and may be secured to the rim in any suitable manner either by forming the same at the time the rim is formed or by forming the plate separately and attaching the two together.

If desired the plate 38 may be provided with a portion 39 of increased thickness and which portion 39 is disposed adjacent the recessed portion 37 of the rim 36.

When the parts are in the position shown in dotted lines in Figure 2, the end of the bolt 17 will be retracted from the recess 37 of the rim 36 and through the opening in the plate 38, and will be held retracted against the stress of the spring 20 by means of the cam surfaces 30. This will permit the removal or the application of the rim 36. After the rim has been placed in position and the lever 28 moved about its pivot 31 the cam surfaces 30 will assume positions

shown in full lines in said figure, to permit the bolt 17 to be shifted by the spring 20 and the end of the bolt will then pass through the plate 38 and snap into the recess 37, the lever 28 being forced against the side of the casing 12 by such action of the spring.

In the form of the invention shown in Figure 3, the spring 40, which is arranged in the recess 13, operates to push the bolt 17 in a direction to project its extremity into the recess 37. In order to accomplish this result the end 41 of the spring 40 rests against the bottom 16 of the recess 13, while the end 42 is secured to the bolt in any suitable manner. Obviously the recess 13 is of a suitable length to permit the expansion of the springs 20 or 40.

With this improved construction it will be manifest that a rim may be readily removed or replaced without the necessity of employing special tools for the purpose and it is also obvious that any number of these fastening devices may be employed upon a wheel.

While the preferred forms of the invention have been herein shown and described, it is to be understood that various changes may be made in the details of construction and in the combination and arrangement of the several parts, within the scope of the claim, without departing from the spirit of this invention.

What is claimed as new is:—

A vehicle wheel, a demountable rim therefor, a series of locking devices for the rim, each of said locking devices embodying a casing carried by the wheel adjacent the periphery thereof, a bolt slideable in the casing and through the periphery of the wheel to engage the rim for securing the latter, said bolt being adapted to be retracted to unfasten the rim, a spring housed within the casing and tending normally to move the bolt in one direction, a cam device pivotally connected with one end of the bolt and operable upon the wall of the casing for moving the bolt in a direction in opposition to the stress of the spring, said cam device being disposed within the confines of the planes of the upright walls of the casing, a lever connected with the said cam device, said lever being foldable substantially flat against a lateral face of said casing, and a projection on the face of the casing adjacent the edge of the lever for protecting the lever when the latter stands adjacent the face of the casing.

In testimony whereof I have signed my name to this specification.

CALVIN J. WHITE.
